CLAIM

The ornamental design for a beverage tray, as shown and described.

DESCRIPTION

FIG. 1 is a top plan view of a beverage tray showing my new design;

FIG. 2 is a front elevation view thereof, all other side elevations being a mirror image;

FIG. 3 is a bottom plan view thereof; and

FIG. 4 is a perspective view thereof in a reduced scale.

Fig. 1

Fig. 2

Fig. 4

Fig. 3
